COMBINED BAG AND CLOSURE

John A. Farmer, Lancaster, Pa.

Application July 5, 1935, Serial No. 30,005

5 Claims. (Cl. 229—62)

This invention relates to packages, and more particularly to means for closing or sealing bags.

In my prior application Serial No. 745,121, filed September 22, 1934, I have shown and described a 5 method of and means for sealing bags, such means comprising a closure member or sealing tab of cardboard or the like adapted to be placed over the end of the bag and secured thereto.

It has been found in practice, however, that it is 10 somewhat difficult to properly position the sealing tab on or apply it to the mouth of a filled bag, and furthermore, that the accurate folding over of the end of the bag, as described in said prior application, presents somewhat of a problem.

The general object of the present invention, therefore, is to provide improved means for and method of assembling the bag and sealing member, and folding over the ends of the former, 20 when desired.

In order that the invention may be readily understood, reference is had to the accompanying drawings forming part of this specification, and in which:

25 Fig. 1 is a plan view showing my improved method of assembling the bag and sealing member;

Fig. 2 is a transverse section on the line 2—2 of Fig. 1;

30 Fig. 3 is a central vertical section through the assembled bag and sealing member;

Fig. 4 is a similar view showing the sealing member and upper part of the bag as they appear after the bag has been filled and closed;

35 Fig. 5 is a fragmentary plan view showing the bag and sealing member assembled in a slightly different relation;

Figs. 6 and 7 are views similar to Figs. 3 and 4, but showing the arrangement illustrated in Fig. 5;

40 Fig. 8 is a perspective view showing how the closure member may be used to hold the end of the bag open for filling; and

Fig. 9 is a fragmentary side elevation showing 45 the sealing member and bag as they appear after the bag has been filled and closed.

Referring to the drawings in detail, I designates my closure tab or sealing member, which is preferably formed with straight ends and with 50 skirt portions 1^a and 1^b having rounded edges, as illustrated in Fig. 1 and as shown and described in my said prior application. The edges of the skirt portions may, however, be made straight, if desired.

55 The tab or closure member is formed of some suitable more or less resilient and relatively stiff

sheet material, such as heavy paper, tag board, cardboard or fiber board, which tends to hold its shape, and is formed with a score line 2 about which it may be folded, said score line being shown as located substantially centrally of the tab. 5

The bag, which is designated by the numeral 3, may be formed of any suitable flexible material such as paper, cellulose sheeting, metal foil or the like.

In carrying out the present invention, I provide means for assembling this sealing tab or member and the bag before the latter is filled, that is to say, while the bag is in flat condition. This may be conveniently accomplished by means of an assembly board A having at its end a strip 10 or flange B and at its sides guide strips or flanges C. The width of the board between the flanges C is substantially equal to that of the bag and of the tab or closure member.

In assembling the parts, I first take a tab or 20 closure member in its flat condition and place it on the board A between the flanges C and with one of the curved edges abutting against the stop flange B. Furthermore, the tab is laid upon the board with the side having the score line upwards, if, as preferred, the scoring is done upon one side only of the tab. By the term "score line" however, I intend to include a row of perforations or any other means by which the sheet is weakened so that it may be readily folded, and in 25 case perforations extending through the sheet are used, it is of course immaterial which side of the tab is placed upwardly.

Having placed the tab or closure member in the 30 position described, and having coated either the end portion of one side of the bag or a median strip or zone of the tab with a suitable adhesive, as indicated at 5 in Fig. 1, the end portion of the bag is applied to the central portion of the tab or closure member, as shown in Fig. 1, the guide 35 strips C serving to properly center and position the bag with respect to the ends or side edges of the tab or closure member. Preferably the portion of the tab beyond the bag end is left uncoated, or free from adhesive. The proper longitudinal 40 position in which the bag is to be placed may be indicated by a suitable mark or notch on the guide strips C. It will, of course, be understood that only one side of the bag is thus secured to the tab or closure member by means of the adhesive, the other side of the bag being left free, so that the end of the bag may be readily opened. Fastening devices may be employed, instead of adhesive, if 45 desired.

50 In the form of the invention illustrated in Figs. 55

1, 3 and 4, I have shown the end of the bag applied to the tab or closure member in such a position that portions of the bag end lie both above and below the fold or score line 2. In other words, 5 the upper edge 4 of the bag is placed above the score line 2, as viewed in Figs. 1 and 3. After the tab or closure member has thus been secured to one side of the top of the bag, in flat condition, as shown in Fig. 3, the bag may be readily opened 10 by squeezing or pressing together the opposite side edges of the tab, as shown in Fig. 8, this causing the end portions of the bag to separate, and the free side to bulge outwardly. When in this position, the bag may be readily filled. After the bag 15 has been filled, the tab or closure member is folded down over the end of the bag, and the end portions of the bag are likewise folded over on themselves along the score line 2, as shown in Fig. 4, the tab or closure member completely enclosing 20 the folded bag end. After the closure member and bag end have thus been folded to the position shown in Fig. 4, they are secured in such folded position by means of a plurality of fastening devices, such as staples 6 or the like, which 25 extend through both legs of the tab or closure member and the folded end portions of the bag, which are enclosed between the same. The resulting package is similar to that illustrated and described in my above mentioned prior application. 30

It will of course be understood that a diagonal line such as shown at 7 in Fig. 9 may be formed on the tab or closure member to indicate that the corner of the package may be cut off to provide a pouring opening, as in my said prior application.

Instead of attaching the bag to the tab or closure member, in the position shown in Fig. 1, in which the edge 4 of the bag is parallel with but 40 spaced from the score line 2, I may assemble the bag and closure member in the relative position shown in Fig. 5, in which the upper edge 4 of the bag is caused to substantially coincide with the score line. When, therefore, the bag has been 45 filled and the tab or sealing member 1 is folded down from the position shown in Fig. 6 to that shown in Fig. 7, it does not result in folding the end portions of the bag, but merely encloses them. The parts are held in this position by means of 50 fastening devices 6, the same as described in connection with Fig. 4, and for many types of material, this method of closing the bag end will be found entirely satisfactory.

From the foregoing, it will be understood that 55 the same general method of assembling the bag and closure member may be employed for producing either the arrangement shown in Figs. 1, 3 and 4, in which the end portions of the bag are folded over with the tab, or the arrangement 60 shown in Figs. 5, 6 and 7, in which the end portions of the bag are not folded over, but are merely brought together in parallel relation and then enclosed by the tab or sealing member. The difference in results depends solely upon the relative

position in which the bag and tab are assembled prior to filling, namely, whether they are assembled in the relation shown in Fig. 1 or in the relation shown in Fig. 5.

In the practical carrying out of my invention, 5 I contemplate that a bag manufacturer may assemble bags and closure members in flat condition and sell them to manufacturers of fluent material who will fill and seal the bags. Thus, the assembled bag and closure member, such as illustrated in Figs. 1 and 3 or in Figs. 5 and 6, constitutes of itself an article of manufacture. 10

While I have shown and described my invention as applied to tabs or sealing members such as illustrated in my said prior application, it will, 15 of course, be understood that the invention is applicable also to the assembling of bags with combined closures and handles such as illustrated and described in my copending application Serial No. 30,006 filed July 5, 1935. 20

What I claim is:

1. As an article of manufacture, a flexible bag having the margin of one side only of its open end secured to a flat tab of sheet material of a width substantially equal to that of the bag, the other side of said bag being free, and said tab having a weakened fold line extending parallel with and adjacent the edge of the bag end. 25

2. As an article of manufacture, a flexible bag having the margin of one side only of its open end secured to a flat, relatively stiff tab of sheet material of a width substantially equal to that of the bag, the other side of said bag being free, and said tab extending substantially beyond the 30 bag end and being formed with a score line about 35 which it may be folded, said line extending parallel with and adjacent the edge of the bag end.

3. As an article of manufacture, a flexible bag having the margin of one side only of its open end secured to a relatively stiff, resilient, normally 40 flat member of sheet material, terminating substantially at the side edges of the bag, said member, when compressed laterally, being capable of assuming a curved form, and when in such form, serving to open the end of the bag so that it may 45 be filled, and said member being foldable on itself to enclose the bag end.

4. As an article of manufacture, a flexible bag having the margin of one side only of its open end secured to a flat, relatively stiff tab of resilient 50 sheet material, the other side of said bag being free, said tab terminating substantially at the side edges of the bag and extending for a substantial distance longitudinally thereof.

5. As an article of manufacture, a flexible bag having the margin of one side of its open end secured by adhesive to a foldable tab of relatively stiff, resilient sheet material, said tab terminating substantially at the side edges of the bag and extending longitudinally beyond the end thereof, the portion of the tab beyond the bag end being free from adhesive. 55

JOHN A. FARMER.
